UNITED STATES PATENT OFFICE.

RICHARD W. MUELLER, OF PITTSBURGH, PENNSYLVANIA, ASSIGNOR TO KEROTEST MANUFACTURING COMPANY, OF PITTSBURGH, PENNSYLVANIA, A CORPORATION OF PENNSYLVANIA.

FIRE-PROTECTIVE MEANS FOR WELLS.

Application filed January 25, 1927. Serial No. 163,377.

This invention relates to means for automatically shutting off the flow of oil or gas from a well in the event of fire, said means being operable through the action of an adjacent fire.

5 A prime aim is to provide such a protective means with a cut-off valve adapted to be operated by air or another medium under pressure, which is normally restrained and inactive by matter fusible from the heat of an ordinary flame and disposed at various locations such as adjacent to the floor and other parts of the derrick, the casing head valve, and the distributing lines.

10 15 Another object is to provide novel fuse links or members in which molten fusible matter will not impede the valve-closing action of the compressed air and the like, in which the fusible material acts as a seal, in 20 which the links may be recharged with fusible material, in which appropriate connections are provided for communication with the valve-actuating cylinder and with the source of actuating medium.

25 30 Various additional objects and advantages will either be pointed out or become apparent from a consideration of an operative embodiment as described hereinafter and illustrated in accompanying drawings.

In said drawings:—

Figure 1 shows the improvements primarily in diagram;

Figure 2 is a partial elevation of a derrick floor and the well parts extending above the 35 same or supported thereon; and

Figure 3 is an enlarged detail longitudinal sectional view taken through one of the fuse links.

In the drawings, 10 designates a conventional well casing extending above the floor 11 of a derrick. Communicating with casing 10 and appropriately supported on the derrick as usual, are one or various distributing pipe lines 12. The discharge of gas 45 and oil from casing 10 is under control of the usual gate valve 13 while each distributing line 12 has a usual regulating and cut-off valve 14 therein.

According to the present invention, I 50 provide a valve structure 15 which is in communication with casing 10, and, although shown as disposed above the casing head valve 13, it may be arranged on either side of said valve 13. The valve structure

15 is adapted to operate automatically to 55 close the casing 10, or an outlet therefrom, and thereby close the well upon the outbreak of a fire adjacent to the well parts and apparatus previously described.

Referring more specifically to the valve 60 structure 15, it preferably includes a casing section 16 in which a normally retracted gate valve 17 and its stem 18 are slidably disposed. Said stem also slides through an intermediate section 19 directly through a 65 stuffing box 20 thereof, and a cylinder 21; the latter at each end as at 22 having packing or stuffing boxes for sealing co-action with said stem 18. Operating within the cylinder 21, is a piston 23, which is carried 70 by stem 18.

A pressure medium is adapted to enter the cylinder 21 in the event of fire to co-act with piston 23 so as to slide stem 18 and accordingly the valve 17 to closed position. 75 Said medium may be compressed air stored in one or more containers 24 although it is to be realized that any other appropriate means or source may be employed. Said containers may be removable and of the refillable type. The said containers 24 are piped to communicate with cylinder 21 under control of fuse links or members 25. Each link 25 has an end 26 detachably connected to a pipe 27 which may lead from manifolds 28 80 arranged in communication with the containers 24. Joint connections 29 extend laterally from each link 25 and have pipes 30 detachably clamped thereto at 31 which lead to one of two manifolds 32 in communication through pipes 33 with cylinder 21. The bores 34 of the respective links 25 are 85 designed to establish communication between the ends 26 and connection 29 in case of fire, but such bores are normally sealed or closed 90 at constricted portions 35 thereof by readily fusible metal or the like 36. By way of example, such metal 36 may be designed to melt at 212° F. Should the metal 36 melt, it would be forced by the compressed 95 air to a location in bore 34 beyond the bore of the connection 29 which is closer to the end containing metal 36 than the other end, so that it will not enter said bore or impede the supply of compressed air to the cylinder 100 21. Fused metal may be removed from the bores 34 or be replaced upon the removal of screw plugs 37 normally sealing the bores.

In order that the fusible metal 36 may be replaced in sealing contact with the links, the metal is preferably in the form of a cylinder arranged to engage the links by means 5 of screw threads at 38.

As will be understood, the fuse links 25 are employed in any desired number and are arranged at various locations about the floor 11, other parts of the derrick, and the valves 10 and piping. Accordingly, in the event of fire, one or more of the links 25 will be so affected by heat so as to melt the metal 36 thereof, thus permitting compressed air to 15 flow from a container 24, through a manifold 28, a pipe 27, a link 25, a pipe 30, a manifold 32, a pipe 33, and cylinder 21, so that it will impinge against piston 23 and thus slide rod 18 and move valve 17 to closed position, thereby preventing further emission of gas 20 and oil from the well.

The outer end of the valve stem 18 as shown by Figure 2, is threaded, and is designed to receive a hand wheel 34 by means 25 of which the valve 17 may be raised to open position after it has been closed by the operation above described; it may also be employed for locking the valve 17 against movement. It will be understood that when 30 the parts are set for automatic operation this hand wheel 34 is removed from the valve stem.

Various changes may be resorted to provided they fall within the spirit and scope of the invention as defined by the appended claims.

35

I claim:

1. In combination with a well, a closure valve therefor, a cylinder and piston associated with said valve, means for passage of a pressure medium to said cylinder to 40 actuate the piston to close the valve, and fusible material normally closing said means.

2. In combination with a well, a closure valve therefor, a cylinder and piston associated with said valve, means for passage 45 of a pressure medium to said cylinder to actuate the piston to close the valve, fusible material normally closing said means, and means operable to move the valve following 50 a closing operation.

3. In combination with a well, a closure valve therefor and a source of power medium, a cylinder, a piston on said valve and disposed in said cylinder, a manifold, a 55 pipe connection between the manifold and cylinder, and pipe connections between said source and said manifold normally closed by fusible material.

I testimony whereof I hereunto affix my signature.

RICHARD W. MUELLER.
